United States Patent Office

Des. 223,896
Patented June 20, 1972

223,896

JUG

John S. Frazer, Pequannock, N.J., assignor to Union
Carbide Corporation, New York, N.Y.

Filed Jan. 20, 1971, Ser. No. 108,258

Term of patent 14 years

Int. Cl. D9—01

U.S. Cl. D9—42

F / G. 1.

FIG. 2.

FIG. 3.

FIG. 4.

FIG. 1 is a perspective view of a jug showing my new design;

FIG. 2 is a side elevational view, the opposite side being a mirror image of the side shown;

FIG. 3 is an elevational view looking from the right of FIG. 2; and

FIG. 4 is a bottom view.

I claim:

The ornamental design for a jug, as shown and described.
